UNITED STATES PATENT OFFICE.

VINCENZO PRITELLI, OF ROME, ITALY.

AIRSHIP.

1,351,301.

Specification of Letters Patent. Patented Aug. 31, 1920.

Application filed July 23, 1918. Serial No. 246,394.

To all whom it may concern:

Be it known that I, VINCENZO PRITELLI, a subject of the King of Italy, and residing at 137 Via Merulana, Rome, Italy, have invented certain new and useful Improvements in Airships, of which the following is a specification.

The invention relates to airships and its object is more particularly to provide an airship which is capable to navigate at high altitudes, to rise rapidly and to travel at great speed and which is easily controlled and combines a considerable lifting power with a maximum carrying capacity.

With these and other objects in view, the invention consists substantially in the construction as hereinafter described and as shown in the annexed drawings, in which

Figures 1 and 2 show the airship in side elevation, Fig. 2 being drawn in continuation of Fig. 1 the land wheels being omitted,

Fig. 3 is an end elevation,

Figs. 4 and 5 are a longitudinal section on line E—F—G—H—I—K of Fig. 6, Fig. 5 being drawn in continuation of Fig. 4, and

Fig. 6 is a cross section of the airship.

In the form of construction shown in the drawings, the balloon is built up with fifteen ballonnets which are arranged as follows: one large ballonet —1— in the top part, four ballonnets —2— in the bottom part, two at the right and two at the left hand side of the balloon, four smaller ballonnets —3— in the lengthwise extending spaces between the ballonnets —1— and —2—, two ballonnets —4— in the bottom part between each two ballonnets —2—, a ballonet —5— at the forward and a ballonet —6— in the rear end of the balloon. Four ballonnets —7— are arranged in the central space between the ballonnets —1— and —2— and six ballonnets —8— are placed three in the forward and three in the rear end of the balloon.

These fifteen ballonnets are inclosed within a framework built up with steel tubes bent into ovoidal hoops —9—, and inside the framework are provided hoops 9' to hold the ballonnets in place and in spaced relation.

The ovoidal hoops —9— have a varying size and shape in accordance with the varying cross section of the balloon, and they are interconnected by lengthwise arranged aluminium tubes and stayed by aid of steel girders 10' which hold them in place and

allow a lower platform P being secured to the framework by means of outside suspensions p', this said platform being also built up with aluminium tubes and steel girders. 60

The envelop —10— of the framework consists of aluminium plates which are fastened on the ovoidal hoops —9— and on the steel girders, and this aluminium sheeting incloses also the lower platform, where it is provided with openings closed by shutters to serve as windows.

The platform is divided into five compartments such as —11—, —12—, —13—, —14— and —15—, of which those —11—, —13— 70 and —15— contain the navigating rooms, the living quarters for the crew and passengers, the provisions, also the power plant which is suitably split up, for example, by housing the motors for the propellers 75 —18—, —19—, —20—, —21—, —22— and —23— in the forward compartment, the motor for the propellers —24— in the central and the motor for the propellers —25— in the rear compartment, while the compartments —12— and —14— serve preferably to contain wheels —16— for traveling on land and the compartment —12— also an observation car —17— adapted to be lowered from the airship for reconnoitering and similar purposes. Gangways 15', extending alongside compartments 12 and 14, provide means for access from one compartment to another. 85

The airship is constructed so that it may be easily taken apart and its length be increased, if desired, by mounting additional hoops more particularly in the main section of the balloon and by providing additional ballonnets in accordance with the increased length of the balloon. 90

The balloon is easily accessible between the spaced ballonnets so that these latter may be readily inspected and repaired when required, and easy access is thus afforded to an upper platform —26— which carries the motor for driving the propeller —27—. 100

It is evident that this provision of a plurality of suitably disposed and lengthwise extending ballonnets within the balloon prevents the safety of the airship being interfered with through one of the ballonnets getting out of order and any damages thereof may be readily repaired, and the 110 stability of the airship will thus never be disturbed.

The ballonnets are covered with a double 65
ply cloth with an inside rubber layer which
is doubled at the rear end where the hydro-
gen produces the maximum pressure during
flight.

Each ballonet is divided inside into a 70
plurality of vertical cells 8' which com-
municate between them by means of open-
ings provided in the vertical partitions, and
10 a lengthwise extending diaphragm within
each ballonet divides the same into two
parts, an upper and a lower one. The upper
part which takes up about two thirds of the
entire cross sectional area, is filled with
15 hydrogen, while the lower part contains air
intended to compensate the varying pres-
sure of the hydrogen at the various alti-
tudes and under the varying atmospheric
conditions. These horizontal diaphragms
20 are arranged so that they may lay them-
selves against the lower surface of the re-
spective ballonet when the hydrogen has
reached the maximum pressure. The hy-
drogen spaces of the various ballonnets are
25 in open intercommunication through pas-
sages 17', as clearly shown in Fig. 5. The
ballonnets —5— and —6— arranged re-
spectively at the forward and the rear end
30 of the balloon, serve to control its horizon-
tal position. These ballonnets are divided
into two halves by aid of a loosely arranged
diaphragm which is adapted to lay itself
against half the upper or the lower surface
35 of the ballonet. They are provided with an
inlet and an outlet piping for the air of
compensation, in order to maintain more
easily the longitudinal equilibrium and to
facilitate the ascent and descent of the air-
ship.

40 Lengthwise arranged tubes —33— serve
to interconnect the air chambers of the
ballonnets by aid of valves of usual type
which close against outgoing pressure, but
open freely under ingoing pressure, also to
45 supply air to the compensating chambers
when the pressure of the hydrogen tends to
diminish, a blower —34— being arranged
at the mouthpiece of the tubes —33— to
blow air into, or draw air from, the com-
50 pensating chambers.

At high altitudes where the atmosphere
is very rare, the pressure of the hydrogen
increases and the air of compensation is
thus caused to escape and to enter the spaces
55 between the ballonnets, from where it passes
through openings in the ceiling into the
compartments —11—, —13— and —15—,
which said openings are provided with
automatic control valves, so as to supply
60 air for respiration when the airship is fly-
ing at high altitudes.

The propellers may work independently
one from the other and at different speeds,
so that the airship may be readily caused

to travel in any desired direction, which 65
also facilitates the work of the rudders and
the ascent and descent of the airship and
maintains the same more securely at the
desired altitude.

For this purpose, the propellers —18— to 70
—23— and —27— are arranged around the
airship along the line of the largest cross
section, where the air is denser on account
75 of the compression produced by the nose of
the air ship during flight. Two propellers
—24— are placed laterally of the central
compartment and provided with reversible
blades for a ready forward and backward
80 drive, while two other propellers —25—
are placed at the stern end of the balloon
laterally of the rear compartment. These
latter propellers —25— are provided with
swiveling bearings so that their angular
position respecting the horizontal axis of
85 the airship may be varied, which arrange-
ment serves also to facilitate the ascent and
descent of the airship and to maintain more
securely its equilibrium.

The required dirigibility and stability of 90
the balloon are obtained by means which
comprise horizontally arranged wings
—28— provided with a mobile rear end so
that their inclination may be varied and the
ascent and descent be facilitated, vertical
95 wings and steadyng surfaces, an upper one
—29— and three lower ones —30—, which
serve to secure longitudinal stability, three
vertical rudders —31— and a twoplane
rudder —32— arranged astern at a higher
100 level than the platform.

It will be understood that many of the
constructional details as hereinbefore set
forth may be varied within the scope and
the purpose of the invention.

What I claim is:

An airship including a series of spaced 105
ballonnets, diaphragms dividing the bal-
lonnets into hydrogen and air chambers,
the hydrogen chambers of the respective
ballonnets being in open communication,
and means for delivering air under pres-
sure to the air chamber of any or all of the
ballonnets to force the gas therefrom, a
platform supported by the ballonnets, pro-
pellers arranged on the line of maximum
length transverse the longitudinal dimen-
sion of the air ship, a vertical wing mounted
above the ballonnets, a plurality of vertical
wings arranged below the ballonnets, and a
plurality of rudders.
